UNITED STATES PATENT OFFICE.

EDMUND C. HEYN, OF CATONSVILLE, MARYLAND, ASSIGNOR TO THE B. V. D. COMPANY, OF NEW YORK, N. Y., A CORPORATION OF DELAWARE.

UNDERGARMENT.

1,280,028.

Specification of Letters Patent. Patented Sept. 24, 1918.

Application filed December 7, 1915. Serial No. 65,495.

To all whom it may concern:

Be it known that I, EDMUND C. HEYN, a citizen of the United States, and resident of Catonsville, county of Baltimore, State of Maryland, have invented a certain new and useful Improvement in Undergarments, of which the following is a specification.

My invention relates to undergarments and more particularly to union suits of the sleeveless or athletic type and has for its object to provide such garments with an improved shoulder construction whereby a universally satisfactory fit is secured and the degree of comfort to the wearer is increased. Other objects of my improvement will appear from the description hereinafter and the features of novelty will be pointed out in the appended claims.

In the accompanying drawings which illustrate an example of my invention Figure 1 is a front view of a garment including my improvement; Fig. 2 is a detail plan view on an enlarged scale and Fig. 3 is a section on the line 3—3 of Fig. 2.

Referring to the drawings the garment comprises the usual front section 5 provided with detachable closing devices 6, the rear section 7 and the leg sections 8. The front section 5 is formed with continuing shoulder sections or straps 9 which extend over the shoulders toward the rear, while the rear section 7 is formed with continuing shoulder sections or straps 10 which extend over the shoulders toward the front of the garment.

The garment in the main, including the shoulder sections or straps 9 and 10, is preferably constructed of a woven material which is substantially inelastic. The free edges 9^a and 10^a of the shoulder sections 9 and 10 are spaced from each other and are connected by means of an insertion 11 of relatively elastic material, the insertion 11 having its opposite ends secured respectively to the shoulder sections 9 and 10 by sewing

in any customary manner. The insertion 11 preferably has a tubular form produced by folding said insertion upon itself at opposite edges so that said opposite edges are adjacent to and possibly in engagement with each other preferably though not necessarily along the major median line of the insertion. These opposed edges are connected by means of an elastic seam 12 which if the said edges meet along the major median line of the insertion also extends along said major me-

dian line and may pass entirely through the said insertion so as to divide same into two parallel tubes or simply connect said opposed edges without passing through the one layer of insertion material. In either case the said elastic seam 12 is also connected with the shoulder sections 9 and 10 for instance by the stitching whereby the said sections and said insertion are secured together and is of relatively less elasticity than the insertion 11 itself. With this arrangement the stretch of the insertion 11 is limited and is arrested at a predetermined point to prevent excessive and harmful stretching of said insertion whereby permanent distortion thereof is avoided. The elasticity of the seam 12 is always sufficient to permit said insertion 11 to yield sufficiently under all strains to secure a maximum degree of comfort to the wearer and thus in no way interferes with the proper and intended operation of said insertion. At the same time with my improved shoulder construction the insertion 11 has a smooth inner or lower surface which contacts with the shoulder of the wearer and is free from any ridges or uncomfortable projections. The insertion is also easily incorporated in the garment and may be constructed in any desired length and then cut into sections of the required size.

My improved insertion and shoulder construction adds materially to the comfort and wearing qualities of the garment and requires no special cutting of said garment before being incorporated therein, thus adapting it for use in any undergarments, particularly those of the athletic or sleeveless type.

Various changes in the specific arrangement shown and described may be made within the scope of the claims without departing from the spirit of my invention.

I claim:

1. In an undergarment, shoulder sections of relatively inelastic material forming continuations respectively of the front and rear of the garment, an elastic shoulder insertion connecting said shoulder sections and an elastic seam extending lengthwise of said insertion and connected with said shoulder sections, said seam intentionally arranged to have less elasticity than the insertion whereby the stretch of the latter is limited.

2. In an undergarment, shoulder sections of relatively inelastic material forming con-

tinuations respectively of the front and rear of the garment, an elastic shoulder insertion connecting said shoulder sections and having its opposite edges folded upon itself into engagement with each other and an elastic seam extending between said shoulder sections and connecting the edges of said insertion together and intentionally arranged to limit the stretch of said insertion.

10 3. In an undergarment, shoulder sections of relatively inelastic material forming continuations respectively of the front and rear of the garment, an elastic shoulder insertion

connecting said shoulder sections and having its opposite edges folded upon itself and meeting along the major median line of said insertion and an elastic seam extending between said shoulder sections and through said insertion along said major median line and connecting the opposite edges of said insertion together, said seam having less elasticity than said insertion whereby the stretch of the latter is limited.

In testimony whereof I have hereunto set my hand.

EDMUND C. HEYN.
